OTHER PUBLICATIONS

Arelli Assassyn wheel, a copy of which is enclosed as Exhibit A (no date).

Enkei Wheel, Spider 3, a photocopy of such wheel design being enclosed as Exhibit B (no date).

* cited by examiner

Primary Examiner—Stacia Cadmus

(74) Attorney, Agent, or Firm—Fulwider Patton Lee & Utecht, LLP

(57) **CLAIM**

The ornamental design for a wheel, as shown and described.

DESCRIPTION

FIG. 1 is a perspective view of a wheel, showing our new design;

FIG. 2 is a section view taken along line 2—2 of FIG. 3; and, FIG. 3 is a front elevational view thereof.

The broken line showing of environment in FIGS. 1-3 is for illustrative purposes only and forms no part of the claimed design.

1 Claim, 2 Drawing Sheets

FIG. 1

UNITED STATES PATENT AND TRADEMARK OFFICE
CERTIFICATE OF CORRECTION

PATENT NO. : Des 436,571 S
DATED : January 23, 2001
INVENTOR(S) : Moh Ruslan Ir, Sumantri Cahyono

Page 1 of 1

It is certified that error appears in the above-identified patent and that said Letters Patent is hereby corrected as shown below:

Title page.

Item [56], **References Cited, OTHER PUBLICATIONS**,
after "Arelli Assassyn wheel" delete "a copy of which is enclosed as Exhibit A" and
after "Enkei Wheel, Spider 3" delete " a photocopy of such wheel design being enclosed
as Exhibit B".

Signed and Sealed this

First Day of January, 2002
